LEATHER ROLLING MACHINE

Harry N. Moore, Endicott, N. Y., assignor to
 Endicott Johnson Corporation, Endicott, N. Y.,
 a corporation of New York

Application February 21, 1945, Serial No. 579,130

20 Claims. (Cl. 69—43)

This invention is a novel machine for rolling and smoothing hides of leather or the like, and the principal object thereof is to provide a machine having a plurality of rows of staggered roller balls cooperating with a series of rolls adapted to act upon the opposite surfaces of hides or the like passing therethrough, the balls being arranged in vertical movable individual yokes with the balls in adjacent rows staggered to cover all portions of the surface of the hide, thereby assuring uniform quality of product and high speed production.

Heretofore hides and the like have been rolled by hand methods, the quality of product depending upon the skill of the operator in utilizing a single roller ball actuated by a swinging pendulum-like arm moving back and forth across portions of the hide. Beneath such ball a bed was disposed, raised and lowered by a foot treadle, through a system of levers, the hide being placed on the bed, and as it was raised into contact with the swing ball its position was changed by the operator, who also varied the pressure by use of the foot treadle. Production of rolled hides by such hand method was obviously small although the quality of the work produced was good.

Another method of rolling hides has been heretofore effected by passing the leather through a series of opposed cylindrical rolls, squeezing or rolling pressure being applied pneumatically to the upper set of rolls. But since hides are not uniform in thickness, that is, some have thin and thick areas, obviously only the high spots of the hides were rolled. While production using this latter method was relatively high, the quality of the product was only fair.

I will explain the invention with reference to the accompanying drawings, which illustrate one practical embodiment thereof to enable others familiar with the art to adopt and use the same; and will summarize in the claims the novel features of construction, and novel combinations of parts, for which protection is desired.

In said drawings:

Fig. 1 is a side elevation of my novel multiple ball rolling machine.

Fig. 2 is a top plan view of the machine.

Fig. 3 is a front end elevation of the machine looking at the feed end.

Fig. 4 is an enlarged elevation of the upper portion of the front end of the machine showing the parts illustrated in Fig. 3.

Fig. 5 is an enlarged longitudinal section through a portion of the machine.

Fig. 6 is an enlarged front elevation through 55

one of the roller balls and its operating cylinder. Fig. 7 is a side elevation of the parts shown in Fig. 6.

As shown, the machine preferably comprises spaced parallel base beams 1—1a, preferably I-beams connected together and having uprights 2—2a at their front ends respectively, and uprights 3—3a at their rear ends respectively. A top beam 4 connects the upper ends of uprights 2—2a at the front end of the machine, and a cross-beam 5 connects the upper ends of uprights 3—3a at the discharge end of the machine as shown in Fig. 2.

Extending between the respective uprights 2—3 and 2a—3a above and parallel with the I-beams 1—1a are beams 6 (Figs. 1 and 3) upon the top of which are bolted down a series of spaced bearings 6b for a series of horizontal rolls 7a—8a—9a—10a—11a, said bearings being held in position by bolts 6a or the like, Fig. 1, and the rolls 7a—8a—9a—10a being formed of steel approximately 10" in diameter and about 6' long, the upper peripheries of the rolls 7a—11a inclusive being disposed in the same horizontal plane.

At the front end of the machine, disposed substantially at the level of or slightly below the plane of the upper peripheries of rolls 7a—11a is a feed table 12 for supporting the hides as they are introduced into the machine. Disposed in the horizontal plane of feed board 12 and mounted upon supporting members extending between adjacent beams 6, are filler plates 13, Fig. 1, forming continuations of the feed table between adjacent rolls 7a—11a for guiding the leading edge of the hide to and between adjacent rolls during its passage through the machine. At the rear end of the machine is a table 14 disposed in the plane of the feed boards 12—13 for supporting the rolled hide as it emerges from the machine.

In the drawings five cylinder rolls 7a—11a are illustrated although a greater or lesser number may be used; and as shown in Fig. 2 the journals of the alternate rolls are extended beyond the sides of the frame so that the journals 7b—9b—11b of the rolls 7a—9a—11a extend varying amounts beyond one side of the frame, while the journals 8b and 10b of the rolls 8a and 10a extend varying amounts beyond the other side of the frame. However, if desired, the rolls 7a, 8b, 9a, 10a and 11a may be driven in tandem fashion or in any other desired manner.

As shown, a counter shaft 14 is journaled in brackets 14b on uprights 3—3a at the rear end of the machine parallel with the cylinder rolls 7a—11a but below the level thereof. Journal

10b at one side of the frame is rotated from counter shaft 14 by means of chain 15 running around sprockets 10c—14c, as shown in Fig. 2, while the journal 8b at the same side of the frame is rotated by counter shaft 14 by means 5 of chain 16 running around sprockets 8c—14d. At the other side of the machine the journal 7b is driven from counter shaft 14 by a chain 17 running around sprockets 7c—14e, while journal 9b is driven by chain 18 running around sprockets 9c—14f, and journal 11b is driven by chain 19 running around sprockets 11c—14g, the sprockets 7c—8c—9c—10c and 11c being all of one diameter and the sprockets 14c—14d—14e—14f and 14g being of one diameter.

Counter shaft 14 carries a sprocket 14h intermediate the bearings 14b opposite a sprocket 20a on the shaft of a variable speed-reducing mechanism 20 driven through coupling 21 and speed reduction mechanism 22a from a motor 22 mounted adjacent or upon the base of the machine, a chain 23 running around the sprockets 14h and 20a, as shown. Thus, as the shaft of the motor 22 rotates the counter shaft 14 will be driven at variable speeds to simultaneously rotate the cylindrical rolls 7a—11a inclusive all at the same speed and in the same direction.

Disposed above and cooperating with the series of cylindrical rolls 7a—10a inclusive is a series of rows of roller balls, each row being arranged directly above the related cylindrical roll, as shown more particularly in Figs. 1, 5 and 7, the row of roller balls cooperating with cylinder 7a being numbered 25, while the row of roller balls cooperating with roll 8a being numbered 26, the row of roller balls cooperating with roll 9a being numbered 28; and the row of roller balls cooperating with roll 10a being numbered 28, as shown in Fig. 1.

The roller balls of adjacent rows are staggered so as to overlap, whereby as the hide passes through the machine all portions thereof will be rolled. In the first row of roller balls cooperating with roll 7a, seven balls 25 are shown in Fig. 3. In the next row of roller balls which cooperate with the adjacent roll 8a, six roller balls 26 are arranged in staggered relation to the balls 25 of the first row. The third row of roller balls 27 which cooperate with roll 9a contains seven balls in staggered relation to the balls of the second row; and the fourth row of roller balls 28 which cooperate with roll 10a contains six balls in staggered relation to the balls of the third row. The balls of alternate rows however may themselves be mismatched that is, not necessarily aligned.

Each of the roller balls 25 to 28 is journaled in a yoke 29 (Figs. 5-7) pivoted as at 30 to the lower end of a piston-rod 31, housed in a flat guide block 32 secured by bolts 33 or the like to the flange of a beam 34 extending between side frame members 35 which latter extend between the uprights 2—3, and 2a—3a respectively of the frame, as indicated in Fig. 1; said guide blocks 32 having bolted or otherwise secured thereon cylinders 36 into which the piston rods 31 extend, same carrying pistons 36a on their upper ends within the cylinders. Springs 38 are disposed around the upper ends of the rods 31 between the pistons 36a and the lower ends of the cylinders 36 for normally maintaining the piston rods 31 in elevated position to maintain their respective roller balls 25—28 inclusive out of contact with their related rolls 7a—10a inclusive, as indicated more particularly in Figs. 6 and 7.

Each of the cylinders 36 is connected at its upper end with a pipe 37 (Fig. 5) to an electrically operated air valve 40 disposed upon the top of the beams 4—5 which connect the upper ends of the uprights 2—2a and 3—3a respectively, as shown in Fig. 1, whereby when the related valve 40 is operated, as hereinafter explained, compressed air will be admitted into the upper end of the related cylinder 36 during such time as the valve is open, and the related roller ball 25—28 will be pressed downwardly into forcible contact with its cylindrical rolls 7a—10a against the action of spring 38, and whereby when the related valve 40 is closed the spring 38 will again raise the piston 31 and the related roller ball 25—28 out of contact with its cylindrical roll 7a—10a. When the roller is not in contact with the leather, the roller balls are held approximately one inch above their related rolls 7a—10a by means of the springs 38. Since twenty-six cylinders 36 are indicated in Fig. 2 in the four rows of cylinders, the air valves therefor may conveniently be arranged in two rows on the frames 4 and 5 each containing thirteen air valves 40 as indicated in Fig. 3.

Each of the valves 40 is connected by a pipe 39 to an air tank (not shown) which operates under an air pressure of 60 to 100 pounds per square inch, and preferably the air pressure therein may be increased or decreased as desired by means of a regulating valve (not shown). The air from the tank enters the respective air valves 40 through the pipes 39 (Fig. 5) and is discharged through the respective pipes 37, into the tops of the respective cylinders 36. Thus each cylinder 36 is actuated by a separate valve 40, the particular type or form of valve forming no part of my present invention.

Immediately in front of each roller ball 25—26 is a contact finger 41, preferably formed of metal and having a rounded lower end normally contacting the feed table 12 or table strips 13, said fingers 41 having their upper ends hingedly mounted as at 41a, Fig. 5, to a bracket 42 secured to the underside of a micro-switch 43, Fig. 5, which latter is mounted on an angle iron support 44, each switch 43 being connected by wires in cables 45 leading to the actuating solenoid of its related air valve 40 whereby as each finger 41 is slightly raised, the related switch 43 will be closed, and the electric circuit to the related valve 40 completed to actuate the air valve and admit air into the upper end of the related cylinder 36. The details of the particular micro-switch form no part of my present invention provided that the switch contacts will normally remain open when the fingers 41 are dropped upon the feed tables 12 or 13, and the switch contacts will remain closed when the fingers 41 are raised by the passage of the hide through the machine upon the tables 12—13, the leading edge of the hide as it contacts the successive fingers 41 actuating the related air valves to depress the related roller balls 25—28, and as soon as the hide has passed therethrough, the fingers 41 again dropping by gravity onto the tables 12 and 13, thereby opening the switch circuits and releasing the air pressure from the cylinders 36. In place of the micro-switches 43, electric eyes might be used and mounted in the same relative positions as the switches 43, said eyes controlling the related air valves 40.

In the series of rolls 7a—11a the last roll 11a is of same diameter as the rolls 7a—10a, but 75 preferably covered with a rubber or other soft

resilient coating of substantial thickness. Co-operating with the coated roll 11a is a steel roll 50 of same diameter as the rolls 1a-10a and having its journals extending through vertical guide slots 51 (Fig. 1) in the frame so that the roll 50 maintains gravitational contact with the underlying coated roll 11a except when separated while a hide is passing therebetween. The purpose of the steel roll 50 is to remove any marks from the hide which may have been made thereon by the roller balls 25-28.

Operation

A hide of leather or other material, in semi-finished state or in the proper condition for rolling, is placed by the operator upon the feed table 12 in advance of the first series of roller balls 25. The operator then pushes the leather forward, making contact with the first row of contact fingers 41 in advance of the first row of roller balls 25. The contact fingers 41 of said series of balls are then raised by contact with the leather and the electric switches 43 of related air valves 40 closed, permitting air to enter the related cylinders 36, whereupon the roller balls 25 of the first series are lowered by their cylinders, and pressure is applied to the leather between the balls 25 and the driven roll 1a. The leather is rolled and carried in a forward motion to the next row of roller balls 26, where a similar action takes place, the fingers 41 of the second series actuating the related roller balls 26 as soon as the leading edge of the hide has passed thereunder and thereby raised the said fingers. The action is repeated for the four rows of roller balls 25-28, the leather then passing under the solid steel roll 50 disposed above and extending the full length of the driven rubber covered roll 11a and having slotted bearings 51 so as to be in constant contact with the rubber covered roll 11a, no downward pressure being applied to the roll 50 other than its own weight. As the roll 11a is rubber covered, the action of the rolls 50-11a is such that any marks on the leather that may be left by the action of the preceding series of roller balls 25-28, is removed.

In my multiple ball machine the staggered arrangement of the roller balls 25-28 assures that all parts of the leather will be rolled with accuracy and speed, and the rolled hide will have uniform quality due to the separately actuated multiple ball arrangement.

In place of the micro-switches 43 actuated by the individual fingers 41 on passage of the hide through the machine, other switch devices might be used, if desired; or electric eyes might be used in connection with the individual roller balls 25-28 to control the respective air valves 40. Therefore, I do not limit my invention to the exact form shown in the drawings, for obviously changes may be made therein within the scope of the claims.

I claim:

1. In a leather rolling machine having a series of closely adjacent rolls lying in substantially the same plane and driven at the same peripheral speed and in the same direction; a work table disposed slightly within the peripheries of the rolls; rows of roller balls normally disposed above the respective rolls; trip fingers disposed adjacent and in advance of each roller ball and normally contacting the table; and means actuated by each finger while swung by passage of work on the table thereunder to press the related roller ball towards its related roll, thereby forcibly com-

pressing the work between the related roller ball and related roll.

2. In a machine as set forth in claim 1, said roller balls of adjacent rows being staggered, whereby the entire area of the work will be engaged by the balls while passing through the machine.

3. In a machine as set forth in claim 1, reciprocable members supporting said roller balls respectively; and each roller ball being journaled in a yoke pivotally connected with its related reciprocable member.

4. In a machine as set forth in claim 1, each said finger being inclined and having an upwardly curved lower end adapted to be engaged by and maintained raised during passage of said work thereunder.

5. In combination with a machine as set forth in claim 1, an additional roll trailing the series and covered with a resilient coating, the periphery of the additional roll lying substantially in the plane of said series; and a cooperating roll above the additional roll mounted in movable bearings and normally gravitationally resting upon the additional roll, the work passing between the said additional and cooperating rolls in its passage through the machine.

6. A leather rolling machine comprising a frame; a series of closely adjacent rolls journaled therein, the upper peripheries of the rolls lying in substantially the same horizontal plane; means for rotating the rolls at the same peripheral speed and in the same direction; a work table cooperating with and disposed slightly below the upper peripheries of the rolls; rows of plungers disposed above the respective rolls, each plunger terminating adjacent the plane of its related roll; means for normally yieldably maintaining the plunger in raised position; a roller ball journaled on each plunger; pivoted trip fingers disposed adjacent and in advance of each roller ball and normally resting upon the table; and means actuated by each finger while swung by passage of work on the table thereunder to press the related plunger toward its related roll, thereby forcibly compressing the work between the related roller ball and related roll.

7. In a machine as set forth in claim 6, said roller balls of adjacent rows being staggered, whereby the entire area of the work will be engaged by the balls while passing through the machine.

8. In a machine as set forth in claim 6, each said roller ball being crowned at its center and having rounded edges, and being journaled in a yoke pivotally connected on a horizontal axis with its related reciprocable member; and each ball being normally maintained by said member in spaced relation to its related roll.

9. In a machine as set forth in claim 6, each said finger being inclined and having an upwardly curved lower end adapted to be engaged by and maintained raised during passage of said work thereunder.

10. In combination with a machine as set forth in claim 6, an additional roll trailing the series and covered with a yieldable coating, the upper periphery of the additional roll lying in the plane of the series; and a cooperating roll above the additional roll mounted in movable bearings in the frame and normally gravitationally resting upon the additional roll, the work passing between the said additional and cooperating rolls in its passage through the machine.

11. A leather rolling machine comprising a frame; a series of closely adjacent rolls journaled therein, the upper peripheries of the rolls lying in substantially the same horizontal plane; means for rotating the rolls at the same peripheral speed and in the same direction; a work table cooperating with and disposed slightly below the upper peripheries of the rolls; rows of fluid pressure cylinders disposed above the respective rolls, each cylinder having a plunger terminating adjacent the plane of its related roll; means for normally yieldably maintaining the plunger in raised position; a roller ball journaled on each plunger; each said cylinder having a duct above the plunger connected with a common source of fluid under pressure; a normally closed valve in each said duct; a pivoted trip finger disposed adjacent and in advance of each roller ball and normally resting upon the table; and means for opening the related valve actuated by each finger while swung by passage of work on the table thereunder, thereby admitting fluid into the related pressure cylinder and forcibly compressing the work between the related roller ball and related roll while the said finger is so swung by the work.

12. In a machine as set forth in claim 11, said roller balls of adjacent rows being staggered, whereby the entire area of the work will be engaged by the balls while passing through the machine.

13. In a machine as set forth in claim 11, each said roller ball being crowned at its center and having rounded edges, and being journaled in a yoke pivotally connected on a horizontal axis with its related plunger; and each ball being normally maintained by said plunger in spaced relation to its related roll.

14. In a machine as set forth in claim 11, each said finger being inclined and having an upwardly curved lower end adapted to be engaged by and maintained raised during passage of said work thereunder.

15. In combination with a machine as set forth in claim 11, an additional roll trailing the series and covered with a soft yieldable coating, the upper periphery of the additional roll lying in the plane of the series; and a cooperating roll above the additional roll mounted in slotted bearings in the frame and normally gravitationally resting upon the additional roll, the work passing between the said additional and cooperating rolls in its passage through the machine.

16. A leather rolling machine comprising a frame; a series of closely adjacent rolls jour-

naled therein, the upper peripheries of the rolls lying in substantially the same horizontal plane; means for rotating the rolls at the same peripheral speed and in the same direction; a work table cooperating with and disposed slightly below the upper peripheries of the rolls; rows of fluid pressure cylinders disposed above each said roll, each cylinder having a plunger terminating adjacent the plane of its related roll; means for normally yieldably maintaining the plunger in raised position; a roller ball journaled on each plunger; each said cylinder having a duct above the plunger connected with a common source of fluid under pressure; a normally closed valve in each said duct; a pivoted trip finger disposed adjacent and in advance of each roller ball and normally resting upon the table; a normally open electric switch adjacent each finger adapted to be closed when the finger is swung; and each valve being electrically controlled and connected in circuit with its related switch, whereby each finger when swung by passage of work on the table thereunder will admit fluid into the related pressure cylinder and forcibly compress the work between the related roller ball and related ball while the said finger is so swung.

17. In a machine as set forth in claim 16, said roller balls of adjacent rows being staggered, whereby the entire area of the work will be engaged by the balls while passing through the machine.

18. In a machine as set forth in claim 16, each said roller ball being crowned at its center and having rounded edges, and being journaled in a yoke pivotally connected on a horizontal axis with its related plunger; and each ball being normally maintained by said plunger in spaced relation to its related roll.

19. In a machine as set forth in claim 16, each said finger being inclined and having an upwardly curved lower end adapted to be engaged by and maintained raised during passage of said work thereunder.

20. In combination with a machine as set forth in claim 16, an additional roll trailing the series and covered with a soft yieldable coating, the upper periphery of the additional roll lying in the plane of the series; and a cooperating roll above the additional roll mounted in slotted bearings in the frame and normally gravitationally resting upon the additional roll, the work passing between the said additional and cooperating rolls in its passage through the machine.

HARRY N. MOORE.
